EGG SHAPED ROCKING TOY

Simmons Correia, Jr., 16 Wells St.,
Lawrence, Mass. 01841

Filed Jan. 3, 1967, Ser. No. 5,283

Term of patent 14 years

U.S. Cl. D34—5
Int. Cl. D21—02

FIG 1

FIG 2

FIG 3

FIG 4

FIG 5

FIG. 1 is a front view of an egg shaped rocking toy, showing my new design; FIG. 2 is a side view thereof; FIG. 3 is a top view thereof; FIG. 4 is an open-front view thereof; FIG. 5 is a sectional view taken along the line 5—5 in FIG. 4.

The broken lines in FIGS. 2 and 3 indicate the line of demarcation between the two portions of my design.

I claim:

The ornamental design for an egg shaped rocking toy, as shown and described.
